UNITED STATES PATENT OFFICE.

FRANK C. URSBRUCK, OF NEW YORK, N. Y., ASSIGNOR TO UNDERWOOD TYPEWRITER COMPANY, OF NEW YORK, N. Y., A CORPORATION OF DELAWARE.

TYPE-WRITING MACHINE.

1,052,104.

Specification of Letters Patent.

Patented Feb. 4, 1913.

Application filed July 21, 1910. Serial No. 572,960.

To all whom it may concern:

Be it known that I, FRANK C. URSBRUCK, a citizen of the United States, residing in New York, in the county of New York and 5 State of New York, have invented certain new and useful Improvements in Type-Writing Machines, of which the following is a specification.

This invention relates principally to type-writing machines having two ribbons, either of which may be vibrated to cover and uncover the printing point on the platen, to the exclusion of the other.

The improvements are shown as applied 15 to a two-ribbon machine, like that disclosed in United States Letters Patent No. 926,054, granted to J. C. Doane, June 22, 1909, wherein the ribbons are threaded through separate vibrators or carriers, operated by 20 the usual universal bar, which is vibrated at each type stroke. A shiftable connector has slotted ears to engage either of two wrists projecting from the respective ribbon-vibrating levers, whereby to connect either ribbon-carrier to the universal bar. Usually, 25 the ribbon carriers have been constructed in such a manner that the active carrier and its ribbon rub against the idle ribbon of the other carrier and tend to lift the same, and to smear ink from one ribbon onto the other, 30 and to overcome this objection, I provide a novel carrier through which the forward ribbon is threaded so that the portion of the ribbon covering the printing point lies in 35 front of the carrier, thereby avoiding contact with the rear ribbon or its carrier; the two carriers merely sliding one against the other as they are vibrated. The objection is also made to the use of two-ribbon ma- 40 chines, that the ink is liable to offset or smudge from one of the ribbons on to the other when capital letters are being printed. At such a time, the lower case types strike the upper portion or edge of the idle ribbon and press it against the lower portion of 45 the active ribbon, thereby offsetting ink from one to the other.

One of the objects of the present improvements is to overcome this difficulty; and to 50 this end I effect a separation of the ribbons when capital letters are being printed, so that one ribbon cannot press against the other. The separation is effected by a spring or spring-finger which presses down the car- 55 rier of the idle ribbon. When the lower-case

letters are being written, there is no danger of color offsetting from one ribbon to the other, because the lower case types are beneath the capital types (when in printing positions), and the capital types do not then 60 strike or press the idle ribbon. When the platen is shifted up to enable the capital types to print, said spring or finger becomes effective to hold or pull down the carrier of the idle ribbon, so that the latter will clear 65 the active ribbon. Said finger is pivoted upon the platen shift rail and bears against the lever of either idle ribbon carrier, to throw the idle ribbon down past its normal 70 position of rest, (the platen being in upper case position) so that the active ribbon when vibrated to cover the printing point, will clear the idle ribbon.

Another feature of the invention comprises an improvement on the mechanism to 75 prevent accidental feeding of the idle ribbon, disclosed in United States Letters Patent to J. C. McLaughlin granted June 22, 1909, No. 926,014, wherein arms connected to the ribbon shifting mechanism have fingers which are moved into engagement with the idle spools, or parts connected thereto, 80 to lock the same, while other arms release the remaining spools so that they may turn freely. 85

I provide latches pivotally supported on the frame of the machine and operated by arms controlled by the ribbon-shifting mechanism. The arms rock the latches radially 90 relatively to the spools, to lock one set of spools and release the other set, without liability of accidentally turning said spools and thereby loosening the ribbon.

In the accompanying drawings, Figure 1 is a perspective, showing one form of the 95 invention applied to an Underwood writing machine, parts being omitted. Fig. 2 is a detail perspective of the shiftable frame carrying the spring or ribbon-separating finger and returning cams. Fig. 3 is a detail side 100 view of the ribbon vibrators and operating mechanism in idle position, the platen being in lower case position. Fig. 4 is a sectional plan of the connector and the ribbon-separating mechanism. Fig. 5 is a plan of the 105 ribbon-vibrating mechanism applied to an Underwood writing machine. Fig. 6 is an enlarged detail plan, partly in section, similar to Fig. 4, but showing the opposite ribbon-vibrating lever in idle position. Fig. 7 is a 110

detail perspective of the vibrating levers and ribbon-separating mechanism. Fig. 8 is a vertical sectional view, through said mechanism. Fig. 9 is a rear view, partly in section, of the ribbon-separating mechanism and bracket. Fig. 10 is a rear view of the ribbon-separating mechanism and the vibrating levers, the connector being shown in section, the left-hand ribbon lever being idle. Fig. 11 is a similar view, the right-hand ribbon lever being idle. Fig. 12 is a similar view, both levers being disconnected from the actuator, as in stenciling. Fig. 13 is a front view of a ribbon-winding mechanism for a two-ribbon machine. Fig. 14 is a detail plan of a train of winding gears and the releasable lock therefor. Figs. 15 and 16 are detail side views respectively, showing a spool gear locked against turning, and released. Fig. 17 is a side view, similar to Fig. 3, showing one of the vibrating levers in idle and the other in active position, the platen being in upper case position. Fig. 18 is a detail perspective of the front ribbon carrier.

Types 1 on type bars 2 strike rearwardly through either a rear ribbon 3 or a forward ribbon 4 against the front face of a platen 5 supported on a platen shift rail 6 mounted to rock in frame 7. The rear ribbon is wound on a pair of spools 8 located on opposite sides of the printing point in front of the platen, in cups 9. The web of the ribbon 3 extending between the spools is threaded, in the usual manner, through a vibrator 10 standing in front of the platen 7, so as to lie behind the vibrator and adjacent the platen. The forward ribbon 4 is preferably wound upon a separate pair of spools 11, seated in cups 12, in front of the platen and on opposite sides of the printing point, the web of said forward ribbon being threaded through a vibrator 13 mounted in front of the vibrator 10, which stands next to the platen, so that the ribbon 4 lies in front of the vibrator on the side farthest from the platen. The ribbons are thus separated by the thicknesses of the two vibrators, so as to vibrate without contact or interference with each other, and so that neither ribbon will rub on the other vibrator. The two vibrators or carriers vibrate in contact with each other, one constituting a partial guide for the other, and the rear vibrator being made of very thin material so as to avoid the necessity of mounting the front vibrator at an undue distance from the platen.

The front ribbon carrier 13 (Fig. 18) may be formed of sheet metal, and has a head portion 14 provided with an opening 15 through which the types strike. Opposite arms 16 projecting laterally from the head have upwardly-extending horns 17 to form eyes, through which the ribbon is threaded. The horns 17 have flanges 18 overlying the

head on opposite sides of the opening 15, so that the ribbon will be held flat during the vibration of the carrier to cover the printing point. Forwardly bent lips 19 on the upper ends of the horns facilitate the introduction of the ribbon into the eyes. Fingers 20 on the head project over the flanges 18 and the upper edge of the ribbon to close the upper ends of the eyes to prevent accidental disengagement of the ribbon and carrier when the latter is vibrated. The outer ends of the arms 16 carry upwardly projecting guard prongs 21, which may be offset forwardly away from the rear ribbon, the forward ribbon passing in front of said prongs, whereby it is positively held separated from the rear ribbon, the prongs forming with the horns 17, a pair of open eyes flanking the closed eyes. The upper ends of the guard prongs 21, which project above the head have forwardly bent lips 22 to shunt the lower edge of the rear ribbon behind and clear of the upper edge of the forward ribbon when the ribbons are vibrated. The types force the forward ribbon 4 through opening 15 to the platen, and may also cause the flexible ribbon carrier to yield slightly toward the platen, so that an undue extent of ribbon is not drawn through the carrier.

In this class of machines, either ribbon carrier 10 or 13 is caused to cover the printing point at each type stroke, by any type bar 2, which, when swung to the platen, presses rearwardly a universal bar 23 forming part of a movable frame 24. A ribbon-vibrating yoke or connector 25 is shiftably supported on a bracket 26 on the universal bar frame 24; said connector having slotted ears 27, 28, to engage respectively the projecting wrists 29, 30 carried by ribbon-vibrating levers 31, 32, said ears being spaced apart to free one wrist from its adjacent ear when the remaining ear is engaged with the wrist on the opposite lever. The levers are pivoted intermediate their ends at 33, to the usual bracket 34 on the platen shift rail 6, to shift with the platen as the latter is thrown from lower to upper case position; said levers being pivotally connected at their forward ends at 35, to their respective ribbon carriers 10 and 13. When one of the ears 27 or 28 has been shifted to engage the adjacent wrist 29 or 30 (Figs. 10 and 11) of the ribbon-carrying levers 31, 32, the vibration of the actuator 23, 24 will rock the lever 31 or 32 on its pivot 33 to cause the ribbon vibrator 10 or 13 to cover the printing point. The connector 25 is shifted relatively to the wrists 29, 30 by a cross arm 36 bearing keys 37, 37^a and fixed intermediate its ends to a rock shaft 38 journaled in the frame 7 and having an arm 39 pivoted to a second arm 40 carried by a link 41 fastened at 42, to the connector 25 (Figs. 5 and 11).

To separate the ribbons, when the platen is in upper case position, to prevent smudging, I provide a special yielding finger 43, pivotally supported on a pintle 45 held in ears 46 carried by a frame 47 mounted on an arm 48 projecting from the platen shift rail 6, and having a slot 49 to accommodate a keeper or washer 50 fastened to the bracket, whereby the frame is shiftably secured thereto. A spring 51 presses the finger against the ribbon-vibrating levers. The active vibrator is of course freed from the opposition of this spring, so that the touch of the finger-keys is not harsh. The frame 47 fits between the slotted ears 28, 29 of the connector 25, so as to be shifted therewith, and as one ear engages the wrist on one ribbon-carrying lever to connect it with the actuator 24, the spring-finger 43 slips off of said lever and onto the adjacent, disconnected lever, the free end of the finger being rounded, as at 52, to enable it to slide over the edges of the levers which are beveled as at 53, so that the finger will not catch thereagainst, if the levers are not lying in alignment. When the platen shift rail 6 is in lower case position, the ribbon-vibrating levers 31, 32, lie against a stop 44 on the frame, (Fig. 3). When the platen is shifted to upper case position, both vibrating levers are shifted away from the stop, but the pressure of the spring finger 43 against the idle lever turns it on its pivot 33, and as a result the idle ribbon-carrier is prevented from having as great an upward movement as the active ribbon-carrier. The idle carrier is thus caused to lie below the active carrier, when the two are at rest in upper case position, (Fig. 17,) and the active carrier, when vibrated, shifts the lower edge of its ribbon past the upper edge of the idle ribbon, so that the two ribbons do not overlap, and hence smudging of ink from one ribbon onto the other (due to the lower case types pressing the ribbons together) is avoided. The pressure of the spring-finger 43 against the idle ribbon-vibrating lever, when the parts are shifted to upper case position, throws the wrist of such lever out of register with the slot in the co-acting ear on the connector (Figs. 3, 4, 6 and 8). The idle lever is arrested by one of two opposite stops 54 on the frame 47. Said stops preferably have inclined or cam faces and as the connector is shifted from side to side, said cam faces alternately engage the wrists of the respective levers (when idle) to restore the wrists to register with the slots in the ears, such return taking place while the ear is moving toward its wrist. Thus, each wrist is guided into its slot.

The pairs of ribbon spools 8 and 11 are mounted on upright shafts 55, journaled in frames 56 and having gears 57 fast thereon. Between the spool gears 57, on one side of

the machine is a winding gear 58, fast on an upright shaft 59, turned by a bevel gear 60 constantly in mesh with a bevel gear 61 on a drive shaft 62. The shaft 59 is journaled in ears 63 carried by a rocking lever 64 pivoted at its lower end at 65. The shaft 59 and rocking lever 64 with their co-operating parts, are duplicated on the opposite side of the machine, the rocking levers being operated by a lever 65^a mounted on the rock shaft 38 controlling the ribbon shifting mechanism, said lever having a link 66 connecting its lower end with the left hand rocking lever 64, its upper end being connected by a link 67 with the right hand rocking lever. When the rocking levers are swung toward each other by the operation of the cross arm 36 on the rocking shaft 38 (Fig. 13), the winding gears 58, (as set forth in said patent) are meshed with the gears 57 of the inner spools 11, to wind the front ribbon 4; and when the rocking levers are shifted away from each other, they mesh the gears 58 with the spool gears 57 of the outer spools 8, to wind the rear ribbon 3.

Upon each rocking lever 64 are secured oppositely extending arms 68 terminating in fingers 69, to operate latches 71 which thereby are caused to alternately lock the pairs of ribbon spools 8 and 11. Said latches are pivoted at 72 to the frames 56, opposite each spool gear 57, to rock substantially radially into and out of mesh with the teeth of said gears, so that the latter will not be turned by the engagement of the latches with or their disengagement from the gears. The arms 68 vibrate in a plane transversely to the plane in which the latches rock, necessitating a loose connection between the arms and latches. Such connection may be simply effected by providing the latches with slots or recesses 70, in which the fingers 69 of the arms are accommodated. When the levers 64 are rocked to mesh the winding gears 58 with one or the other pair of spool gears 57, the arms 68 are vibrated to mesh one of the latches of each pair with the pair of idle spool gears, and to disengage the remaining latch of each pair from the pair of active spool gears, whereby the inner spool gears are in use; the outer spool gears are locked against turning, and vice versa.

Variations may be resorted to within the scope of the invention, and portions of the improvements may be used without others.

Having thus described my invention, I claim:

1. In a typewriting machine, including a platen shiftable from lower to upper case position and vice versa, the combination with a ribbon mechanism including a pair of ribbon carriers, levers connected thereto, an actuator, and a shiftable connector to couple either lever separately with the actuator, the levers shiftable with the platen,

of a spring-pressed finger shiftable with the connector to engage and depress the idle lever and its carrier when the parts are in upper case position.

5. 2. In a typewriting machine, including a platen shiftable from lower to upper case position and vice versa, the combination with a ribbon mechanism including a pair of ribbon carriers, levers connected thereto, an actuator, and a shiftable connector to couple either lever separately with the actuator, the levers shiftable with the platen, of means to engage and depress the idle lever and its carrier when the parts are in upper case position.

15. 3. In a typewriting machine, including a platen shiftable from lower to upper case position and vice versa, the combination with a ribbon mechanism including a pair of ribbon carriers, levers connected thereto, an actuator, and a shiftable connector to couple either lever separately with the actuator, the levers shiftable with the platen, of a spring-finger to effect the detrusion of 25 the idle ribbon carrier below the active ribbon carrier when the parts are in upper case position.

4. The combination with a ribbon mechanism including a pair of ribbon vibrators, 30 pivotally supported levers coupled to the respective vibrators, an actuator vibrating at each type stroke, and a shiftable connector having slotted ears to engage wrists on the respective levers to couple either lever 35 separately to the actuator, of a shiftable supported frame embraced between and shifted by the ears, and a yielding-finger pivoted to the frame to engage and depress either lever when idle to bring the idle ribbon below the active ribbon.

5. In a typewriting machine, the combination with a platen shiftable to either of two positions by a platen shift rail, and a ribbon mechanism including a pair of ribbon carriers or vibrators, levers coupled to the respective vibrators and pivotally supported by the platen shift rail to shift therewith, an actuator vibrating at each type stroke, and a shiftable connector to couple 45 either lever separately to the actuator, of a finger shiftable with the connector to throw either vibrator lever to inactive position when the platen is in upper case position, and means to return the lever to position to 50 be engaged by the connector when said lever is to be coupled to the actuator.

6. In a typewriting machine, the combination with a platen shiftable to either of two positions by a platen shift rail, and a 60 ribbon mechanism including a pair of ribbon carriers or vibrators, levers coupled to the respective vibrators and pivotally supported by the platen shift rail to shift therewith, wrists on the levers, an actuator vibrating at each type stroke, and a shiftable

connector having slotted ears to engage the wrist on either lever to couple it to the actuator, leaving the other lever idle, of a shiftable yielding finger to throw the idle lever to inactive position below the active 70 lever when the platen is in upper case position, thereby throwing the wrist on said lever out of alinement with the slot in its co-acting ear, and cams shiftable with the connector and leading to the slots in the respective ears thereof, to return the wrists of the idle lever to position to be engaged by its slotted ear when said lever is to be coupled to the actuator.

7. In a typewriting machine, the combination with a platen shiftable to either of two positions by a platen shift rail, and a ribbon mechanism including a pair of ribbon carriers or vibrators, levers coupled to the respective vibrators and pivotally supported by the platen shift rail to shift therewith, wrists on the levers, an actuator vibrating at each type stroke, and a shiftable connector having slotted ears to engage the wrist on either lever to couple it to the actuator, leaving the other lever idle, of a shiftable yielding finger to throw the idle lever to inactive position below the active lever when the platen is in upper case position, thereby throwing the wrist on said lever out of alinement with the slot in its co-acting ear, and a shiftable stop for each lever to arrest the throw thereof caused by the pressure of the said finger, and effective to return the idle lever so that its wrist may 90 be engaged by its co-acting ear.

8. In a typewriting machine, the combination with a platen shiftable to either of two positions by a platen shift rail, and a ribbon mechanism including a pair of ribbon carriers or vibrators, levers coupled to the respective vibrators and pivotally supported by the platen shift rail to shift therewith, wrists on the levers, an actuator vibrating at each type stroke, and a shiftable connector having slotted ears to engage the wrist on either lever to couple it to the actuator, leaving the other lever idle, of a bracket on the platen shift rail, a frame mounted to shift on the bracket 105 with the connector, a yielding finger carried by the frame to effect a separation of the ribbons, when vibrated, at the time when the platen is in upper case position, and cam faces supported by the frame to arrest the 110 idle lever and to return it to position to be engaged by its slotted ear when the frame is shifted.

9. In a typewriting machine, the combination with a platen shiftable to either of two positions by a platen shift rail, and a ribbon mechanism including a pair of ribbon carriers or vibrators, levers coupled to the respective vibrators, and pivotally supported by the platen shift rail to shift there- 125 130

with, an actuator vibrating at each type stroke, and a shiftable connector to couple either lever separately to the actuator, of key-controlled means to shift the idle lever, and its carrier relatively to the active lever and its carrier when the platen is in upper case position, to effect a separation of the ribbons when the active carrier is vibrated, and means to limit the throw of the idle lever, and to restore it to position to be coupled with the actuator when the connector is shifted.

10. In a typewriting machine, the combination with a platen shiftable to either of two positions by a platen shift rail, and a ribbon mechanism including a pair of ribbon carriers or vibrators, levers coupled to the respective vibrators, and pivotally supported by the platen shift rail to shift therewith, an actuator vibrating at each type stroke, and a shiftable connector to couple either lever separately to the actuator, of key-controlled means to shift the idle lever and its carrier relatively to the active lever and its carrier when the platen is in upper case position, to effect a separation of the ribbons when the active carrier is vibrated, and a cam face for each lever to limit its throw when in idle position and to return it to be coupled with the actuator when the connector is shifted.

11. In a typewriting machine, the combination with a pair of vibratory ribbon carriers, ribbon vibrating levers having wrists, an actuator vibrated at each type stroke, a shiftable connector having slotted ears to engage either wrist separately, and guides to direct the wrists into the ears.

12. In a typewriting machine, the combination with a pair of vibratory ribbon carriers, ribbon vibrating levers having wrists, an actuator vibrated at each type stroke, a shiftable connector having slotted ears to engage either wrist separately, a spring finger to throw the idle ribbon vibrating lever to inactive position, thereby moving its wrist out of register with the slot in the co-acting ear, and guides to direct the wrists into the ears.

13. In a typewriting machine, the combination with a ribbon mechanism including two pairs of ribbon spools, gears therefor, a pair of winding gears, rocking levers supporting the winding gears, means connecting the levers to swing the winding gears into mesh with either pair of spool gears, latches pivoted on a stationary support to move radially into and out of mesh with the spool gears, to lock the idle gears against turning and to release the active gears, and arms carried by the rocking levers and loosely connected with the latches to control the latter.

14. In a typewriting machine, the combination with a ribbon mechanism including two pairs of ribbon spool gears, a pair of

winding gears, rocking levers supporting the winding gears, and means to shift the levers to mesh the winding gears with either pair of spool gears, of pivotally supported latches movable radially into and out of mesh with the spool gears, and having openings, and arms on the levers, the ends of said arms being accommodated in the openings to rock the latches to lock the idle spool gears and release the active spool gears without turning said spool gears.

15. In a typewriting machine, the combination with a ribbon mechanism including vibratory ribbon carriers, means to effect the vibration of either ribbon carrier separately, means to throw either carrier when idle to an ineffective position, whereby when the platen is in upper case position, the active ribbon will be vibrated past the idle ribbon, one of said carriers having a head with a type opening therein, horns co-acting with the head to form eyes on opposite sides of the type opening, means to close the eyes against the accidental disengagement of the ribbon therefrom, guard prongs offset from the horns, in front of which the front ribbon passes to separate it from the rear ribbon, the upper ends of the prongs being bent forwardly over the upper edge of the ribbon to prevent the lower edge of the rear ribbon from engaging the upper edge of said front ribbon when the rear carrier is vibrated.

16. In a typewriting machine, a ribbon vibrator or guide comprising a head having a type opening therein, eyes located on opposite sides of the opening, means to prevent the disengagement of the ribbon from the eyes during its vibration, and open eyes flanking the closed eyes to enable the ribbon to be threaded through the vibrator to lie in front thereof.

17. In a typewriting machine, a ribbon carrier comprising a head having a type opening, horns projecting upwardly beside the head to form eyes, the upper ends of the horns being bent forwardly to facilitate the entrance of the ribbon, fingers closing the upper ends of the eyes against the accidental disengagement of the ribbon therefrom, and flanges on the horns overlapping the head to hold the ribbon flat.

18. In a typewriting machine, the combination with a ribbon mechanism employing two ribbons and separate ribbon carriers therefor, one of said carriers having a head with a type opening therein, horns projecting upwardly beside the head and co-acting therewith to form eyes, means to prevent the accidental disengagement of the ribbon from the eyes, means to hold the ribbon flat during the vibration of the carrier, and guard prongs offset from the horns to effect a separation of the two ribbons and co-operating with the horns to form open eyes in which the ribbon is accommodated.

19. In a typewriting machine, a ribbon carrier comprising a head having a type opening, upwardly projecting horns lying adjacent the head on opposite sides of the type opening, fingers extending forwardly from the head and passing close to the upper ends of the horns to close the eyes formed between the horns and the head against the accidental disengagement of the ribbon therewith, and guard prongs extending about parallel with the horns and spaced apart therefrom to form open eyes offset from the closed eyes.

20. In a typewriting machine, a ribbon carrier comprising a head having a type opening therein, oppositely projecting arms on the head, horns projecting upwardly from the arms and co-acting with the head to form eyes on opposite sides of the type opening, flanges on the horns, overlying the head to hold the ribbon flat, fingers closing the upper ends of the eyes against the accidental disengagement of the ribbon therefrom, and guard prongs projecting upwardly from the arms and co-acting with the horns to form open eyes.

21. In a two-ribbon typewriting machine, a ribbon mechanism including a pair of vibratory ribbon carriers, means to vibrate either to the exclusion of the other, the front carrier comprising a head having a type opening, eyes lying on opposite sides of the head to hold the ribbon flat during the vibration of the carrier, fingers to prevent the accidental disengagement of the ribbon from the eyes, and guard prongs offset from the eyes to separate the front ribbon from the rear ribbon and to prevent the interference of the lower edge of the rear ribbon with the upper edge of the front ribbon when the rear carrier is vibrated.

22. In a typewriting machine, the combination with a platen, of a pair of ribbon vibrators standing one directly in front of the other in front of the platen, the rearmost vibrator having its ribbon threaded therethrough, to lie behind the plane between the vibrators and adjacent the platen, the forward vibrator having its ribbon threaded therethrough to lie in front of said plane.

23. In a typewriting machine, a ribbon vibrator having a head provided with a type opening and eyes on the sides of the head, through which the ribbon is threaded, and also provided with ribbon-guiding prongs at the sides of the eyes said prongs offset forwardly from the head.

24. In a typewriting machine, a ribbon-carrier comprising a head having a type opening and having members on the sides of the type opening forming ribbon-guiding eyes, said members including flanges which overlie the head forming slots to hold the ribbon flat.

25. In a typewriting machine, a ribbon-

carrier comprising a head having a type opening and having members on the sides of the type opening forming ribbon-guiding eyes, said members including flanges which overlie the head to hold the ribbon flat, said carrier also having ribbon-guiding prongs at the sides of said eyes, said prongs offset forwardly from said head.

26. In a typewriting machine, a ribbon carrier comprising a head having a type opening, horns projecting upwardly beside the head to form eyes, fingers closing the upper ends of the eyes against accidental disengagement of the ribbon therefrom, and flanges on the horns overlapping the head to hold the ribbon flat.

27. In a typewriting machine, a ribbon carrier comprising a head having a type-opening, horns projecting upwardly beside the head to co-operate therewith to form eyes, and flanges on said horns overlapping the head forming a slot to hold the ribbon flat.

28. In a typewriting machine, a ribbon carrier comprising a head having a type-opening, horns projecting upwardly beside the head to co-operate therewith to form eyes, flanges on said horns overlapping the head to hold the ribbon flat, and other ribbon-guiding horns at the sides of the first-mentioned horns.

29. In a two-ribbon typewriting machine, a rear ribbon carrier, a front ribbon carrier adjacent said rear carrier, comprising devices through which the ribbon is threaded, said devices having at their upper portions forwardly projecting parts which prevent said carrier becoming fouled with the lower edge of the rear ribbon.

30. In a typewriting machine, the combination with a plurality of ribbon vibrators, of shiftable means for silencing either one and concomitantly bringing the other one into use, a support on which said vibrators may rest when idle and means controlled by shiftable means for yieldingly restraining the silenced vibrator from movement against said support.

31. In a typewriting machine, the combination with a plurality of ribbon vibrators, of a universal bar operable at the type strokes, a shiftable connection for connecting either vibrator with the universal bar and silencing the other vibrator, a support on which said vibrators may rest when idle, and a spring connected to said shiftable connection to shift therewith to position to restrain the silenced vibrator against said support.

32. In a typewriting machine, the combination with a platen shiftable upwardly for writing capital letters, of a pair of ribbon vibrators, shiftable means for silencing either vibrator and bringing the other into use, and means effective when the platen is shifted up to write capital letters for caus-

ing the silenced ribbon vibrator to occupy an abnormally low normal position.

33. In a typewriting machine, the combination with a platen shiftable upwardly for writing capital letters, of a pair of ribbon vibrators, shiftable means for silencing either vibrator and bringing the other into use, a yielding device connected to said shiftable means for coöperation only with the silenced vibrstor, to cause the same to drop relatively to the active vibrator when the platen is shifted up for writing capital letters.

34. In a typewriting machine, the combination with a platen, of a ribbon vibrator

arranged to move the ribbon between a type and said platen, a flat member comprising a straight edge over which the ribbon passes in feeding across said vibrator, and a flange overlying said flat member.

35. In a typewriting machine, the combination with a ribbon vibrator of the ordinary type, of a ribbon vibrator having flat members and ears on said flat members, and flanges arranged to hold said ribbon flat against certain of said flat members.

FRANK C. URSBRUCK.
